UNITED STATES PATENT OFFICE.

PAUL M. LOCKWOOD, OF KANSAS CITY, MISSOURI.

DESIGN FOR A TIRE-COVER.

54,273.

Specification for Design.

Patented Dec. 9, 1919.

Application filed April 17, 1919. Serial No. 290,863. Term of patent 14 years.

To all whom it may concern:

Be it known that I, PAUL M. LOCKWOOD, a citizen of the United States, residing at Kansas City, in the county of Jackson and State of Missouri, have invented a new, original, and ornamental Design for a Tire-Cover, of which the following is a specification, reference being had to the accompanying drawing, forming part thereof.

The figure is a perspective view of a tire cover, showing my new design.

The design consists of two annular side members 1 and 2, connected by a band consisting of outer, relatively wide stripes 3 and 4 and centrally located, narrower stripes 5—6; the side members 1—2 and stripes 3—4 differing in color and the stripes 5—6 differing in color.

I claim:

The ornamental design for a tire cover, as shown and described.

PAUL M. LOCKWOOD.
